UNITED STATES PATENT OFFICE.

WILLIAM H. BOLTHOFF, OF DENVER, COLORADO, ASSIGNOR TO THE MILNER MANUFACTURING COMPANY.

PERMUTATION-PADLOCK.

SPECIFICATION forming part of Letters Patent No. 488,516, dated December 20, 1892.

Application filed June 18, 1892. Serial No. 437,114. (No model.)

To all whom it may concern:

Be it known that I, WILLIAM H. BOLTHOFF, a citizen of the United States, residing at Denver, in the county of Arapahoe and State of Colorado, have invented certain new and useful Improvements in Combination-Padlocks; and I do hereby declare the following to be a full, clear, and exact description of the invention, such as will enable others skilled in the art to which it appertains to make and use the same.

My invention relates generally to locks and especially to that class known as combination padlocks.

15 The object of my invention is to provide a strong and durable lock and also one which will be water tight, so that the tumblers and other mechanism will be protected and preserved.

20 The nature of the invention consists in certain combinations and constructions all as will be fully described in the specification and pointed out in the claim, reference being had to the accompanying drawings wherein:—

25 Figure 1 is a front elevation showing the lock open. Fig. 2 is a side elevation with the shackle removed. Fig. 3 is a side elevation of the shackle closed. Fig. 4 is a top plan of Fig. 2. Fig. 5 is a longitudinal section of arm b.

30 Referring to the drawings, A represents the body or barrel of the lock which may be made any desired size or shape.

B represents the shackle and C the knob which controls the tumblers. The shackle B fits snugly within the passage a in the top of the barrel and is made of two parts or arms b and b' respectively, said arms being pivoted together at c. Arm b is made integral with its leg b² and is provided with a series of

35 notches b³ that correspond in number to the tumblers employed. This leg b² is recessed at a' and also has a hole a³ extending upward as shown. Secured to barrel A and fitting within this hole a³ is a post C' having a hook shaped head c' adapted to engage with a pin

b⁹ extending across the hole a³, near its lower end, and thus keep the shackle from being drawn out of the barrel when the lock is opened. The arm b' has a projection b⁴ on its lower end said projection having notches 50 to correspond to those in leg b². Projection b⁴ fits in the recess a' and is flush with the recess when the shackle is closed. The arms b and b' are provided on their upper ends with a recess and seat respectively, lettered 55 b⁶ and b⁵ which fit the latter within the former when the shackle is closed.

D is the dial plate which is provided with the usual characters. c⁴ is the guide post which is secured to the knob C and extends 60 up through the hole d in the leg b and serves to guide the tumblers.

The operation of the device is as follows:— The lock being closed the combination is operated in the usual manner, when all the tumblers are disengaged from the notches b³ the shackle is drawn up, or the barrel down as the case may be, the arm b going up vertically until the hook c' on post C' engages the pin crossing the hole in said arm. At this 70 point the arm b' drops taking the position shown in Fig. 1, the projection b⁴ entering recess a' in the leg b².

What I claim as new is

In a padlock the barrel A having the passage a a post within said passage, the shackle formed of two pivoted arms b and b', arm b' having the projection b⁴ and arm b having the recess a' and the hole a³, said recess being adapted to receive projection b⁴ when the 80 shackle is opened and a post C' secured to the barrel and adapted to extend within hole a³, and engage the pin b⁹, substantially as described.

In testimony whereof I affix my signature in 85 presence of two witnesses.

WILLIAM H. BOLTHOFF.
